Primary Examiner — Calvin E Vansant*Assistant Examiner* — Tyenne A. Fulton-Crosson(74) *Attorney, Agent, or Firm* — CIONCA IP Law P.C.(57) **CLAIM**

The ornamental design for a chair seat as shown and described.

DESCRIPTION

FIG. 1 is a front left perspective view of a chair seat showing my new design;

FIG. 2 is a front top perspective view thereof;

FIG. 3 is a rear top perspective view thereof;

FIG. 4 is a left top perspective view thereof;

FIG. 5 is a right top perspective view thereof;

FIG. 6 is a top plan view thereof; and,

FIG. 7 is a top perspective view thereof.

The broken lines shown on the seat and backrest of the chair seat depicts stitching that does not form part of the claimed design. The broken lines illustrating the chair base shows environmental structure that forms no part of the claimed design.

1 Claim, 7 Drawing Sheets(56)
